CLAIM

I claim the ornamental design for a valve, as shown and described.

DESCRIPTION

FIG. 1 is a perspective view of a valve of my new design; FIG. 2 is a front elevational view of the valve of FIG. 1; FIG. 3 is a rear elevational view of the valve of FIG. 1; FIG. 4 is a right side elevational view of the valve of FIG. 1; FIG. 5 is a left side elevational view of the valve of FIG. 1; FIG. 6 is a top plan view of the valve of FIG. 1; and, FIG. 7 is a bottom plan view of the valve of FIG. 1. The broken lines in the figures are for the purpose of illustrating portions of the valve that form no part of the claimed design.
